UNITED STATES PATENT OFFICE.

FAUSTO MUSSO, OF NEWCASTLE, WYOMING.

WIRE STRETCHER.

Application filed August 1, 1924. Serial No. 729,553.

To all whom it may concern:

Be it known that I, FAUSTO MUSSO, a citizen of the United States, residing at Newcastle, in the county of Weston and State of Wyoming, have invented certain new and useful Improvements in Wire Stretchers, of which the following is a specification.

This invention relates to an improved wire stretching device, which is adapted for drawing fence wire, such as barbed wire, so that it will be rendered extremely taut, before it is fastened to the fence posts.

One feature of the invention is the provision of a rotary hand crank which is provided with a portion constituting a drum, upon which one end of an anchored pull wire is wound, when the crank is rotated.

Another feature of the invention is the provision of a novel device for connecting the free end of the fence wire to the so-called drum, so that during the longitudinal travel of the latter, during its rotation, an end-wise pull will be exerted on the fence wire, to render the latter extremely taut before it is nailed to the posts.

The numerous other features and their resultant advantages will become apparent during the following description and drawings.

In the accompanying drawing, forming a part of this application, and in which like numerals are employed to designate like parts throughout the same:

Figure 1 is an elevational view of the improved wire stretcher, showing the method of using the same.

Figure 2 is a bottom plan view thereof.

Figure 3 is a detail perspective view of an improved connector used between the ends of the pulled wire and the wire to be pulled.

Referring now to the drawings in detail, the reference character 1 designates a pull wire which is preferably plane. As is customary, one end of this wire is anchored to any suitable stationary support. The fence wire, which is to be pulled, is designated by the reference character 2. A barbed wire is shown in the present instance. In order to adapt the fence wire, for use in conjunction with my invention, the free end is looped, as indicated at 3, and the extremity thereof is wrapped about the body of the wire, as indicated at 4, to maintain the wire in a looped condition.

As before intimated, an improved con-

nector, which is generally indicated by the reference character 5, is used in conjunction with the fence wire 2, being more specifically adapted to be associated with the loop 3. 60 This connector, by preference, comprises a flat strip of metal, which has one end directed laterally and then bent to form a seat, for the bight portion of the wire loop 3. The bent end of the strip is bifurcated, at 65 6, thus forming a pair of hooks 7, which constitute the aforesaid seat. The edges of the hooks are notched as at 8, and the opposed stretches of the wire loop pass therethrough to assist in maintaining the wire in place. 70 As seen more clearly in Figure 3, a gradual bend of the metal strip is made, so that a bearing surface 9 is provided at the junction of the laterally directed portion and the body portion of the strip. The opposite end of the strip, which is preferably reduced in width is directed laterally downward, as at 10, and the free extremity thereof is brought to a point, and this point is bent to provide an additional hook 11. This hook 80 11 is, as seen in Figure 1, adapted to be connected to the wrapped portion of the fence wire.

A hand crank 12 is provided, and the long arm of this crank carries a laterally directed cylindrical portion, which functions as a drum 13. This drum 13 is provided intermediate its ends with a hole 14, and in practice, one end of the pull wire 1 is inserted into this hole. The drum under the action of the hand crank is adapted to be rotated in the direction of the arrow A, it being obvious that during the rotation, the portion of the pull wire attached to the drum will be wound on the latter, as indicated at 15.

In operation, the free end of the pull wire 1 is inserted through the opening 14 in the drum 13, and a turn is made in the direction of the arrow to provide at least one wrapping of the wire about the drum, to insure effective starting of the winding operation. Assuming that the fence wire has been looped, as before stated, this loop is connected with the member 5, as indicated in Figure 1. In this position, the member 5 is disposed vertically, and the hook 11 on the depending end is connected with the wrapped portion of the wire. It is with this arrangement that the member 5 is maintained in a truly horizontal plane, 105 during the operation of the device. It will

also be observed, that when the parts are in operative position as shown, the wrapped end of the wire 1 has that portion adjacent to the wrapping extended between the furcations 6. Furthermore, the so called drum is seated for rotation against the curved bearing surface 9. Moreover, the drum 13 is placed in position before the bight portion of the loop 3 is engaged with the hooks 7. Thus, the wire loop is disposed in a manner, to maintain the drum in its seat or bearing. With the parts in this position, it is obvious that by grasping the crank 12, and rotating it in the direction of the arrow A, the ends of the wire 1 will be wound upon the drum. As the latter is connected with the member 5, it is obvious that during the longitudinal travel of the drum, a longitudinal pull will be exerted upon the fence wire 2, through the medium of the member 5. The fence wire is thus drawn tautly so that it can be nailed to the post in this condition.

It is thought that a careful consideration of the foregoing description, taken in connection with the accompanying drawings, will suffice to enable a clear comprehension of the invention to be obtained. Therefore, a more lengthy description is deemed unnecessary.

While I have shown and described a specific embodiment of the invention, it is to

be understood that minor changes coming within the scope of the adjoined claim may be resorted to, if desired.

35

I claim:

In a wire stretching device, a connector in the form of a strip, of metal having one end directed laterally downward and having its extremity bent to form a hook, the opposite end of the strip being bent laterally in a horizontal plane and said last named bent end being bifurcated and the extremities of the furcations being bent to provide a pair of spaced hooks, the bend extending between said horizontally bent ends and the body portion of the strip constituting a bearing seat, a bent wire having one end looped, the bight portion of said loop being seated in said spaced hooks and the twisted portion of the loop being engaged with the first named hook, a separate and independent hand crank having a lateral cylindrical extension functioning as a drum, said drum being seated for rotation in said bearing seat and being partially held in place by said wire loop, and a pull wire extending between said furcations and attached to said drum to be wound upon the latter.

In testimony whereof I affix my signature.

FAUSTO MUSSO.
